COMBINED GAS AND STEAM ENGINE.

1,250,224.

Specification of Letters Patent. Patented Dec. 18, 1917.

Application filed June 10, 1909, Serial No. 501,391. Renewed June 22, 1916. Serial No. 105,293.

To all whom it may concern:

Be it known that I, JÖRGEN REMMEN, a resident of Donora, in the county of Washington and State of Pennsylvania, have invented a new and useful Improvement in Combined Gas and Steam Engines, of which the following is a specification.

This invention relates to explosive engines, and the purpose is to provide an engine of the type specified which is self-starting and reversible, and in which special scavenging and cooling means for the explosion cylinder is provided.

Generally stated the invention consists in providing an explosive or internal combustion engine with means for admitting fluid pressure to the piston for starting purposes, the arrangement being such that the admission of the fluid pressure does not interfere with the explosions in the cylinder, and also providing means for scavenging the explosion cylinder at such times when the fluid pressure medium is not employed.

Heretofore engines have been devised combining explosion and fluid pressure features, but in all such cases as far as I am aware the explosion parts of the engine were inoperative while the fluid pressure parts were in operation, so that while the fluid pressure means served to start the engine they had to be entirely thrown out before the explosions could start. With my arrangement the normal operation of the explosion parts is in no way interfered with by the fluid pressure parts so that while the latter can be used for starting or reversing the engines, the explosions can occur simultaneously therewith and thereby insure the starting of the engine. Other special features will hereinafter appear.

In the accompanying drawings Figure 1 is a vertical cross-sectional view through a cylinder and the main shaft of an explosion engine showing my invention applied thereto; Fig. 2 is in part a side view and in part a vertical section of the air starting valves; Fig. 3 is a view similar to Fig. 1 showing a modification; Fig. 4 is a similar view showing still another modification adapted for heavy stationary and marine engines; and Fig. 5 is a side elevation of the engine shown in Fig. 4.

As shown in Figs. 1 and 2, 1 represents a cylinder having bores of different diameters, namely a small bore 2 which constitutes the explosion space or chamber of the engine and a larger bore 3 which constitutes the space or chamber in which the fluid pressure medium acts and also forms a compressor chamber for scavenging purposes as will hereinafter appear. Working in this cylinder is a piston 4 having the smaller head 5 fitting bore 2 and a larger head 6 fitting the bore 3. This piston is connected by the usual connecting rod 7 to a crank on the main shaft 9 which is mounted in the crank case 10 as is usual with explosive engines. The explosion chamber 2 is provided with suitable inlet and exhaust valves, the inlet valve 11 being shown as adapted to open automatically by the suction in the chamber 2. The exhaust valve 12 is positively operated, the means shown comprising a spring 14 for holding the valve closed and a connecting rod 16 operated from cam shaft 17 driven from the main shaft 9 for opening said valve. The explosion chamber is also provided with igniting devices, not shown. Scavenging valve 20 controls a port into the upper end of the chamber 2, which port 80 communicates with a passage 21 in the walls of the cylinder.

The fluid pressure inlet is through a port 23 which communicates passage 24 with the space 3 in the larger bore of the cylinder 85 above the head 6 of the piston. A three-way valve 25 controls the port 23, passage 24 and lower end of scavenging passage 21, as is shown in Fig. 1. The exhaust from the space 3 is through a port or ports 26 near 90 the lower end of said space, which exhaust port or ports are uncovered by the head 6 when the piston approaches the limit of its downward stroke. The port 26 also serves as the inlet when the piston 6 acts as a 95 pump to force air into the explosion cylinder to scavenge the same. The admission of the fluid pressure to port 23 is controlled by valve 28 working in the chest 29 having the fluid pressure supply connection 30. The valve 28 is normally held closed by a spring 31 and is provided with a stem 32 which is arranged to be actuated by an eccentric or cam 33 on shaft 34 which is driven from the

main shaft 9. Fig. 2 shows the starting valve mechanism arranged for a four cylinder engine so as to admit fluid pressure to said cylinders in alternation.

5 As there shown the shaft 34 is provided with four cam pieces 33 which have a circular central portion 35 and at the opposite ends cam projections 36 which are arranged at 90 degrees to each other. The cams for 10 the various valves are also arranged at 90 degrees to each other so that in the rotation of the shaft 34 alternate valves 28 are opened to admit pressure in succession to the several cylinders of the engine, as will be readily 15 apparent. The shaft 34 is so mounted that it can be moved endwise in either direction, such as by means of a lever 37 so that thereby it is possible to start the engine in either direction. For instance, if the cam shaft is 20 moved from its central position in one direction it brings the cams on one end of the members 33 underneath the valve actuating stems, while if moved in the other direction it brings the cams at the opposite ends of 25 said members underneath said stems. The exhaust valve cam shaft 17 is similarly arranged and will also be moved endwise by the same movement so as to reverse the exhaust valves simultaneously with inlet 30 valves. This reversing arrangement is most suitable for small marine engines and enables the reversing clutch to be dispensed with. For uses where the engine need not be reversible the cam pieces 33 will be circular on one end and have the cams merely on 35 their opposite end. The normal position of the shaft is such that the rollers on the valve actuating stems contact with the circular part of the cam piece.

40 When the engine is to be started the three-way valve 25 is set to the position shown in Fig. 1, cutting off the scavenging passage 21 and connecting the fluid pressure inlet with the space 3 above piston 6. The cam shaft 34 is then moved endwise in the desired direction causing the roller on the valve actuating stem to slide up the cam on the cam piece and thereby lifting the valve 28 and admitting fluid pressure, preferably 45 compressed air to the space 3 above the piston head 6 thereby forcing the piston downwardly. As said piston approaches the limit of its downward movement the head 6 uncovers the exhaust port 26, so exhausting the 50 fluid pressure medium. The cams on shaft 34 open the valves 28 in succession and since the four cylinders of the engine are connected in succession to cranks on the main shaft arranged at 90 degrees to each other the admission of the fluid pressure to the several 55 cylinders in succession naturally starts the engine from any position. During this operation there is no connection whatsoever between the fluid pressure side of the cylinder 60 and the explosive side thereof so that ex-

plosive mixture can be drawn into the cylinder 2 and exploded in the usual way. Consequently the fluid pressure feature can be continued as long as desired or at least until the explosions are properly established. As soon as the explosions are well established the cam shaft is moved back to its normal or neutral position thereby shutting off the air supply. If desired a spring can be arranged to move the cam shaft back to neutral position as soon as the operator releases the starting lever. In this position the head 6 of the piston working in the space 3 acts as a compressor, taking in air through port 26 on its down stroke and compressing the air on its upstroke, the air passing through the three-way cock 25 underneath the valves 28 forcing the latter off its seat and passing back into the air tank. When the air tank is filled the three-way valve 25 can be moved to the position to cause its diametrical port to connect air passage 3 with scavenging passage 21 and its radial port to connect with the air inlet 23. In this position the piston head 6 will begin the scavenging of chamber 2, and also to keep up the pressure in the air tank. In this position there is connection between the space 3 and the valve chest 29 so that on every other upstroke (compression stroke, the engine being a four cycle engine,) when the pressure in the combustion chamber is high enough to keep the scavenging valve 20 shut the air flows to the tank, while on the alternate strokes when there is no pressure in the cylinder 2 the air opens the scavenging valve 20 and scavenges said cylinder. The three-way valve may also be set in position to connect the space 3 and the scavenging passage 21 and blank air inlet 23. In this position the piston 6 merely scavenges the chamber 2 on each alternate stroke, the other strokes merely compressing the air which expands again on the down stroke so that practically no power is lost. This latter is also true when the three-way valve is in the second position described and the pressure in the air tank is approximately the same as the compression pressure in the explosion chamber 2. The air forced through cylinder 2 not only scavenges the same, but also cools the chamber, the piston head, and especially the exhaust valve.

To reverse the engine at any time when running the three-way valve 25 is moved to the position shown in Fig. 1, the ignition or explosive mixture momentarily cut off and the fluid pressure admitted into chest 29.

Fig. 3 shows a slight modification wherein each cylinder is provided with an admission and exhaust slide valve. As here shown each cylinder is provided with a chest 40 in which is a piston valve 41 controlling the flow of fluid from the admission port 42 to the space 3 and also exhausting the same

from said space to exhaust port 48, as will be readily understood. The valve 41 is operated from the eccentric or cam shaft 34 driven from the main shaft and can be reversed in the same manner as described in connection with Figs. 1 and 2, or in the valve connecting rod may be placed an ordinary reversing link movement by means of which the engine can be reversed when desired. 5 This figure also shows an air inlet valve 44 to the scavenging passage 21.

The operation of this modification is substantially as that shown in Figs. 1 and 2, the difference being that the valve 41 positively controls the exhaust as well as the admission to the space 3, and the air inlet valve 44 permits of the drawing in of a scavenging charge of air on the downstroke of the piston into space 3, and closes on the 10 upstroke of the piston so that this air is forced past valve 21 into chamber 2. The valve 41 can also be mechanically operated so as to shut only on the scavenging stroke.

Figs. 4 and 5 show a modification particularly adapted for large marine engines. In this modification the arrangement of valves is substantially the same as shown in Fig. 3, while the valve operating mechanism comprises cam shafts 45 and reversing link 15 mechanism 46 in the connections. It differs from the two former modifications in having a cylinder with only a single diameter bore in which there is a plain piston 4^a, opposite sides of the piston forming heads for coöperation with the chambers or spaces in opposite ends of the cylinder. The lower end of the cylinder is closed by head 1^a and the fluid pressure medium is admitted below the piston and exerts a lifting movement instead 20 of a pushing down movement as in the other form. The fluid pressure medium, however, acts upon the full diameter of the piston and therefore gives a strong lifting effect. By reason of having the fluid pressure space 25 underneath the piston instead of above it, the compression of air for scavenging would occur at exactly the opposite of the right time for scavenging that particular cylinder. Consequently the scavenging passage 30 21^a instead of leading to the top of its own cylinder is cross-connected by pipe 21^b to the next adjacent cylinder, as shown in Fig. 5, so that the air compressed in one cylinder scavenges its mate. With this arrangement 35 it is necessary that at least two cylinders be provided for the engine in order to get the scavenging effect. Air inlet valves 44^a are placed in the cross-connecting pipes 21^b. These may be mechanically operated. The engines described being what are known as four cycle engines, the cam shaft 17 or 45 operating the exhaust valve 12 will of course be rotated at such speed as to open the exhaust valve during each 40 fourth stroke of the piston.

In all forms shown herein any suitable fluid pressure medium may be used. For stationary work or large marine engines the fluid pressure medium is preferably steam, but for automobile and other small engines 70 where a steam boiler cannot be very well applied, the fluid pressure medium will preferably be compressed air which can be supplied by a small compressor operated by the engine and stored in a suitable reservoir, 75 but preferably the engine will act as a compressor as described in connection with Figs. 1 and 2.

The engine described can be positively started by the fluid pressure medium, the 80 reciprocation of the piston so set up drawing in the explosive mixture which is compressed on the subsequent stroke of the piston. The admission of the fluid pressure medium does not interfere at all with the 85 explosive end of the cylinder, so that the explosions may begin as soon as the engine starts and in this way the starting is very reliable and cannot fail. After the engine is started the space in the cylinder in which 90 the fluid pressure medium was applied acts as a compressor for scavenging and cooling the explosion chamber, thereby insuring a clean or unadulterated mixture in the cylinder and making the explosion feature of the 95 engine much more reliable than where no special scavenger is provided for, and also assisting in cooling the cylinder, piston head and exhaust valve. Even when running the engine can be reversed by temporarily cutting off the ignition or the explosive mixture, turning on the fluid pressure medium and properly shifting the valve operating mechanism.

What I claim is:

1. In a combined internal combustion and fluid pressure engine, the combination of a single cylinder, a piston having two heads therein, said cylinder having a chamber for each head, an inlet for an explosive mixture 110 to one chamber of said cylinder and an outlet for exploded gases therefrom, a fluid pressure inlet to the other chamber of the cylinder, an exhaust for said fluid pressure therefrom, and valve mechanism arranged 115 to admit and exhaust a fluid pressure medium to the latter chamber, said valve mechanism being arranged on successive strokes to alternately connect said pressure chamber to said fluid pressure inlet and to said 120 explosion chamber.

2. In a combined internal combustion and fluid pressure engine, the combination of a cylinder having an explosion chamber, a piston having two heads, one in said chamber, a fluid pressure space arranged to co-operate with the second head of said piston, valve mechanism for controlling the admission of fluid pressure to said space, a passage connecting the fluid pressure space to 125 130

the explosion chamber, and a three-way valve arranged to cut off said passage when the fluid pressure medium is operative.

3. In a combined internal combustion and fluid pressure engine, the combination of a cylinder having an explosion chamber, a piston having two heads, one in said chamber, a fluid pressure space arranged to co-operate with the second head of said piston, valve mechanism arranged to control the supply of fluid pressure to said space, a passage connecting said space with the explosion chamber, and a three-way valve arranged to connect said space alternately to the fluid pressure inlet and to the explosion chamber.

4. In a combined internal combustion and fluid pressure engine, the combination of an explosion chamber, a piston having two heads, one in said chamber, a fluid pressure space arranged to co-operate with the second head of said piston, valve mechanism for controlling the supply of fluid pressure to said space, connections between said space and the explosion chamber arranged to scavenge the latter continuously during every second engine stroke when the fluid pressure medium is cut off, and reversing means in the fluid pressure controlled valve operating mechanism.

5. In a combined combustion and fluid pressure engine, the combination of a single cylinder having bores of different diameters, a single piston therein having heads of different diameters, admission and exhaust for explosive mixtures to the smaller bore of said cylinder, a fluid pressure inlet to the larger bore of the piston, an exhaust for the fluid pressure therefrom having no connection with the explosion chamber, a three-way valve controlling said inlet, and mechanism for actuating said valve.

6. In a combined internal combustion and fluid pressure engine, the combination of a single cylinder having bores of different diameters, one of said bores serving as an explosion chamber and the other as a fluid pressure chamber, a single piston in said cylinder having heads of different diameters, admission and exhaust mechanism for explosive mixtures to the explosion bore of the cylinder, a fluid pressure inlet to the larger bore of the cylinder, an exhaust for said fluid pressure therefrom having no connection with the explosion chamber, a three-way valve controlling said fluid pressure inlet, mechanism for actuating said valve, and reversing means in said actuating mechanism.

60 7. In a combined internal combustion and fluid pressure engine, the combination of a cylinder, a piston therein provided with two heads, explosive mixture admission and exhaust valves controlling passages to one head of said piston, a fluid pressure medium

valve arranged to admit fluid pressure to and exhaust it from the other head of said piston, and connections whereby the last named head upon one stroke compresses air for scavenging the explosion cylinder and 70 for the next stroke compresses air for starting the engine.

8. In a combined internal combustion and fluid pressure engine, the combination of a cylinder having bores of different diameters, 75 a piston therein having heads of different diameters, valve mechanism for controlling the admission and exhaust of explosive mixture to one head of said piston, valve mechanism for controlling the flow of fluid pressure to the other head of said piston, and connections from the last named head to the explosion chamber whereby the fluid pressure head compresses air during each alternate stroke and scavenges the explosion cylinder 80 during the intermediate strokes.

9. In a combined internal combustion and fluid pressure engine, the combination of an explosion cylinder, a piston therein, an air pressure space arranged in conjunction with 90 a head of said piston, valve mechanism arranged to control the supply of compressed air to said space, a passage connecting said space with the explosion cylinder, and a three-way valve arranged to connect the 95 space either to the compressed air inlet or to the explosion cylinder or to both, the valve mechanism being arranged when not set to admit fluid pressure to the space in the cylinder to automatically open and permit compressed air generated by the piston to pass to the supply.

10. In a combined internal combustion and fluid pressure engine, the combination of an explosion cylinder, a piston therein, 105 a fluid pressure space arranged in conjunction with the head of said piston, and valve mechanism arranged to control the supply of fluid pressure to said space, said valve mechanism including a valve opening toward the supply of fluid pressure, and means capable of being rendered inoperative for opening said valve, whereby when said valve opening means is inoperative fluid pressure generated by the piston can open 110 said valve and pass to the supply of fluid pressure.

11. In an internal combustion engine the combination of a cylinder, a piston therein having two heads, an inlet for the explosive 120 mixture to one head of said piston and an outlet for exploded gases therefrom, mechanism arranged to open said outlet during each fourth stroke of the piston, an air inlet to the other head of the piston, and a passage for connecting the space at the other head of the piston to the explosion chamber when the exhaust therefrom is open, said passage being controlled by non-positively-125 actuated valves only. 130

12. In an internal combustion engine the combination of a cylinder, a piston therein having two heads, an inlet for explosive mixture to one head of said piston and an 5 exhaust outlet for exploded gases therefrom, mechanism arranged to open said exhaust outlet during each fourth stroke of the piston, an air inlet to the other head of the piston, a passage connecting the space at 10 said other head of the piston with the ex-

plosion chamber, and a non-positively-actuated check valve in said passage seating away from the explosion chamber.

In testimony whereof, I have hereunto set my hand.

JÖRGEN REMMEN.
